CLAIM

(21) Appl. No.: **29/139,320**

The ornamental design for a combined massaging bath mat,
control unit and hose, as shown and described.

(22) Filed: **Mar. 28, 2001**

DESCRIPTION

(30) **Foreign Application Priority Data**

Jan. 9, 2001 (HK) 0110048

FIG. 1 is a front elevational view of one embodiment of a
combined massaging bath mat, control unit and hose in
accordance with my invention;

(51) LOC (7) Cl. **24-04**

FIG. 2 is a rear elevational view thereof;

(52) U.S. Cl. **D24/201**

FIG. 3 is a top elevational view thereof;

(58) **Field of Search** D24/201, 200;

FIG. 4 is a bottom elevational view thereof;

4/541.1, 541.2, 541.3, 541.4, 541.5; 601/167,

FIG. 5 is a left side elevational view thereof;

168

FIG. 6 is a right side elevational view thereof;

D. 233,485 * 10/1974 Krages D24/201

FIG. 7 is a left side elevational view of the mat only;

D. 288,607 * 3/1987 Baumann et al. D24/201

FIG. 8 is a right side elevational view of the control unit
only; and,

D. 305,687 * 1/1990 Walczak et al. D24/201

FIG. 9 is a perspective view of the embodiment shown in
FIG. 1.
